US00D844668S

(12) **United States Design Patent** (10) **Patent No.:** **US D844,668 S**
(45) **Date of Patent:** **** Apr. 2, 2019**

(54) **DISPLAY SCREEN OR PORTION THEREOF
WITH GRAPHICAL USER INTERFACE**

(71) Applicant: **Samsung Electronics Co., Ltd.**,
Suwon-si (KR)

(72) Inventors: **Heon Woo Lee**, Seoul (KR); **Miyeon Park**, Seongnam-si (KR); **Yongman Park**, Yongin-si (KR); **Jakyung Lee**, Seoul (KR); **Hyerim Kwak**, Seoul (KR); **Soyoung Lee**, Seoul (KR)

(73) Assignee: **SAMSUNG ELECTRONICS CO., LTD.**, Suwon-si (KR)

(**) Term: **15 Years**

(21) Appl. No.: **29/628,115**

(22) Filed: **Dec. 1, 2017**

Related U.S. Application Data

(62) Division of application No. 29/608,638, filed on Jun. 23, 2017, now Pat. No. Des. 807,398, which is a division of application No. 29/564,971, filed on May 17, 2016, now Pat. No. Des. 794,048.

(30) **Foreign Application Priority Data**

Nov. 18, 2015 (KR) 30-2015-0058205

CLAIM

The ornamental design for a display screen or portion thereof with graphical user interface, as shown and described.

DESCRIPTION

FIG. 1 is a front view of a display screen or portion thereof with graphical user interface showing our new design according to a first embodiment; and, FIG. 2 is a front view of a display screen or portion thereof with graphical user interface showing our new design according to a second embodiment.

(Continued)

The broken lines at the outer perimeter of the drawings depict a display screen or portion thereof and form no part of the claimed design. The remaining broken lines in the drawings depict portions of the graphical user interface that form no part of the claimed design.

1 Claim, 2 Drawing Sheets
